SYNCHRONIZING DEVICE FOR SELF-PLAYING INSTRUMENTS

Louis Luberoff, Philadelphia, Pa.

Application December 23, 1932, Serial No. 648,710
Renewed May 31, 1934

9 Claims. (Cl. 84—4)

This invention relates to a device for controlling the alternate operation of a plurality of self-playing musical instruments.

An object of the invention is the provision of an arrangement for alternate operation of an organ and a phonograph, whereby the phonograph may be employed to give a definite selection where it is impossible to reproduce the same selection on the organ because of the limited space in which the instrument is adapted to be placed. In other words, the arrangement is such that any type of sound selection with various instruments or the voice especially may be reproduced alternately with the automatic 10 operation of the organ.

A further object of the invention is the provision of an arrangement for alternate operation of a phonograph and organ in which the player roll of the organ console will include 20 means for controlling the proper timing of the stopping of the roll while causing initiation of the playing of a phonograph record which may or may not have its sounds amplified by a mechanism embodied in the organ, the 25 phonograph also including means for controlling the proper timing of the starting of the roll at the end of a phonograph record and vice versa.

This invention will be best understood from a consideration of the following detailed description, 30 in view of the accompanying drawings forming a part of the specification; nevertheless, it is to be understood that the invention is not confined to the disclosure, being susceptible of such changes and modifications which shall define no material departure from the salient 35 features of the invention as expressed in the appended claims.

In the drawings:

Figure 1 is a front view in elevation of an 40 organ and associated console constructed in accordance with the principles of my invention.

Figure 2 is a plan view of the mechanism for controlling a pneumatic alternate operation of an organ and a phonograph.

Figure 3 is a front elevation of the arrangement shown in Figure 2.

Figure 4 is a vertical section taken along the line 4—4 of Figure 5 disclosing an electric control for restarting the player roll after a phonograph has been stopped.

Figure 5 is a section taken along the line 5—5 of Figure 4.

Figure 6 is a detached front view in elevation of a pneumatic switch control of a motor for operating the turntable of a phonograph.

Figure 7 is a vertical section taken along the line 7—7 of Figure 6.

Figure 8 is a fragmentary longitudinal vertical section of a valve mechanism controlling the usual wind motor of a pneumatically operated organ or piano.

Figure 9 is a vertical section of a valve mechanism for starting the wind motor after being stopped and for controlling the energization of a magnet, the organ being always in condition for manual playing.

Figure 10 is a vertical section of another valve controlling mechanism taken along the line 10—10 of Fig. 11.

Figure 11 is a section taken along the line 11—11 of Fig. 10.

Figure 12 is a fragmentary vertical section shown more or less diametrically of an automatic switch actuated by the tone arm of a phonograph, diagrammatically disclosing a circuit and its connection for controlling the operation of the turntable motor of the phonograph, and

Figure 13 shows more or less diagrammatically a circuit for a motor that operates the phonograph.

Figure 14 is a vertical section showing a switch.

Referring more particularly to the drawings, 20 designates generally an organ proper, in which a plurality of dummy pipes 21 are shown in elevation for the purpose of ornamentation.

It will be noted that these dummy pipes, which are usually restricted to only a portion of the height of the organ 20, are shown as of 25 full height of the organ and this is due to the fact that the console 22 is formed independently of the organ.

The lower central portion of the organ is shown at 23 and is provided with a panel forming a closure for the outer end of a chamber which houses the well known type of electrically operated amplifying unit 24. This unit is connected by wires 25 in the usual manner with a loud speaker 26 located behind the panel 27 formed at the upper central portion of the organ.

The console 22 is of the well known type and contains keyboards 28 whereby the organ may be manually played together with the stops 29. The organ is also adapted to be pneumatically 30 operated through a player roll 30.

The console also contains a chamber 31 in which is located a self-playing phonograph 32 having an automatically controlled tone arm 34 and a mechanism for delivering records 35

which are stored in a magazine 36 and which are adapted to be placed in operative relation upon the turntable 37 which is operated by an electric motor 38. Wires 39 connect the tone arm 34 with an amplifying unit 24 and speaker 26 mounted in the organ 20.

As shown more particularly in Figs. 2 and 3, the organ is pneumatically operated by moving a rod 40 by means of a finger-piece 41 to the right in Fig. 3, as indicated by the arrow. The rod 40 is connected to a link 42 which is secured to a bellows 43 carried by a bracket 44 which is secured to the base 45 of a chamber 46 in which the player roll 30 is housed.

15 A switch box 47 is also carried by the bracket 44 and has wires 48 and 49 leading to an electric motor which operates a suction pump, the motor and pump not being shown. An operating arm 50 for a switch located in the box 47 projects from the box and is connected by a link 51 with the outer end of the bellows 43 so that when the rod 40 is moved in the direction indicated by the arrow in Fig. 3, the link 51 will likewise be moved, thereby rocking the switch arm and closing the switch within the box 47. When the switch in the box 47 is closed, the shafts 52 and 53 are revolved through the medium of the gears 54 and 55, shaft 56, chain 57 and its corresponding sprockets on the shaft 56 and the shaft 53 which acts as a re-wind for the sheet roll 30 when it is being unwound from a drum 58 secured to the shaft 52. The shaft 53 carries a drum 59 upon which the sheet roll 30 is rewound as it is unwound from the drum 58.

30 The shaft 53 is driven by means of a chain 60, a sprocket secured to the shaft 53 (Fig. 2) and a crank shaft 61.

40 A pneumatic motor 62 of the slide valve type is employed and the crank shaft 61 controls the slide valves 63 (Fig. 2).

45 As shown more particularly in Fig. 3, the shafts 52 and 53 are mounted in a frame 64 located in the chamber 46. This frame also carries a tracker bar 65 over which the sheet roll 30 is adapted to travel.

50 The sheet roll is provided with a plurality of perforations 66 which are adapted to be aligned with air openings 67 in the tracker bar and these openings are connected by means of pipes 68 with a stack 69. The sheet roll 30 is also provided with additional perforations 70, 71 and 72 which are adapted to be aligned with air openings 73, 74, and 75, respectively, and located in the tracker bar 65. It will be noted that the perforations 66 in the sheet roll 30 which control the operation of the playing of these various notes and instrumentalities of the organ 20 are located inwardly of the perforations 70, 71 and 72. One end of a conduit 76 is connected with the passage 73 in the tracker bar while one end of a conduit 77 is connected with the passage 74 in the tracker bar. A conduit 78 is connected at one end with the passage 75 in the tracker bar 65.

65 The opposite end of this conduit 78 is connected with a chamber 79 in a valve box 80. The opposite end of the conduit 76 is connected with a chamber 81 in the valve box 80. The opposite end of the conduit 77 is connected with a passageway 82 in a casing 83.

70 The stack 69 is provided with a housing 85 which has a pipe 86 connecting the housing 85 with the suction pump so that air is exhausted from the housing 85 and the stack 69 during the

80 operation of the player in the console. A pipe 87 places the housing 85 in communication with a housing 88 located adjacent the casing 83. A pipe 89 connects the pipe 87 with a valve casing 90. A pipe 91 connects the casing 90 with a casing 92 which is connected to the pump 62. A pipe 93 connects a chamber 94 (Fig. 8), located in one end of the casing 92 with the casing 83 as shown in Figs. 2, 3 and 8. A pipe 95 connects a governor housing 96 with a pipe 91.

85 A pipe 97 connects the casing 85 with a valve box 98 carried by the frame 64 and the valve within this box is controlled by means of a finger-piece 99. A second pipe 100 connects the valve box 98 with a chamber 101 formed in the casing 83. A second pipe or conduit 101 connects a chamber 103 in the casing 83 with a pipe 104 that has one end connected with the housing 85 while the other end is connected with the lower end of a valve casing 105. It will be noted that the pipe 102 is connected with the pipe 104.

90 A pipe or conduit 106 connects a chamber 107 with a pipe 108 and the pipe 108 extends to the casing containing the rewind valve.

95 A rod 109 is connected with the governor 100 mechanism located in the casing 96.

100 An operating rod 110 is connected with the lower end of a lever 111 which is pivoted at 112. The upper end of the lever is connected with a link 113 and this link is connected by a rod 114 extending into the governor housing 96. This rod controls the governor 96 and, therefore, regulates the speed of the player mechanism of the console. It will also be noted that the pipe 87 is connected between the casing 88 and the 110 housing 85 on the stack 69 so that the degree of suction is varied in accordance with the tempo desired.

110 A pipe 116, as shown more particularly in Figs. 2, 4 and 5, connects the pipe 100 with a 115 chamber 117 formed in a casing 118. The bottom of the casing, as shown at 119, is provided with a bleeder port 119. A solenoid 120 is secured to the top of the casing 118 and projects into the chamber 117 so that when it is energized it will raise a valve 121 formed of magnetic material away from the pipe 116 so that air from the atmosphere through the port 119 will enter the pipe 116. Wires 122 and 123 are connected with a source of current 124 as shown 125 more particularly in Fig. 12 and the terminals of these wires are connected with switch elements 125 and 126 carried, respectively, by a shaft 127 of the tone arm 34 and a base 129 upon which the tone arm is mounted.

130 The motor 38 for operating the turntable of the phonograph is connected by wires 130 and 131 with a switch 132, the switch being controlled by an arm 133 shown more particularly in Figs. 3, 6 and 13. This switch arm is adapted to be rocked upwardly or downwardly from the "off" position to the "on" position and vice versa.

135 A lever in the form of a plate 135 is hingedly mounted at 136 on a supporting means 137 for the valve casing 80. The plate is triangularly-shaped and is provided with a notch 138 which receives a pin 139 secured to a rod 140. This rod has one end pivotally mounted at 141 with the bellows 143^a. The other end of the rod is pivotally connected at 142 with the outer end of a bellows 143. This bellows is also supported by the member 137. A link 144 connects the outer end of a lever 135 with the upper free end of the operating arm 133 for the switch in the switch box 132.

Referring more particularly to Figs. 6 and 7 it will be seen that a piston valve 150 controls the communication between the pipe 106 and a chamber 151 which is in communication with a passage 152 which connects the bellows 143 with the chamber 151. A diaphragm 153 is connected by a stem 154 with the piston valve 150.

A second piston valve 155 is connected by a stem 156 with a diaphragm 157. The piston valve 155 is located in the chamber 158 and this chamber is connected by a passage 159 with the chamber 107. A perforated covering 160 is secured to one face of the casing 80 so that a passage 161 will connect the atmosphere with the chamber 151 while a passage 162 connects the chamber 158 with the atmosphere.

Referring more particularly to Figs. 4, 5 and 9 it will be seen that a valve 170 normally closes the passage 171 which leads from the atmosphere to the chamber 103. The passage 171 is also in communication with the chamber 172 in which a valve 173 is located and maintained in a normal position by means by a diaphragm 174. The valve 173 normally closes the passage 93, therefore cutting off communication between said passage and a passage or conduit 82 formed in the casing 83. A valve 170 is carried by a diaphragm 175 and this diaphragm is located above the chamber 101.

Referring more particularly to Figure 8 it will be seen that a passage 176 connects a chamber 177 in the casing 92 with the windmotor. The chamber 177 is also in communication with the pipe or conduit 91 through a passage 178. A diaphragm 179 isolates the chamber 177 from the chamber 94 and carries a valve 180 which is adapted to engage the inner end of the passage 176 for cutting off communication between said passage and the pipe 91. It may be noted that the pipe 93 is in communication with the chamber 94.

Referring more particularly to Figs. 10 and 11, it will be seen that the housing 85 contains a chamber 181 which is in communication with the pipe 97. A second chamber 182 is cylindrical in form and is located at right angles to the chamber 181. An annular chamber 183 embraces the chamber 182 and is normally in communication with the said chamber by a port 184. A diaphragm 185 is connected with a valve stem 186 which operates a valve 187 located exteriorly of the casing 85 and cuts off communication between the atmosphere and the chamber 182. It will be noted that the annular chamber 183 has an extension 188 which is in communication with the pipe 87. A pipe 189 connects the housing 85 with the stack 69. Webs 190 and 191 support the valve stem 186 within the cylindrical chamber 182. A spring 192 engages at one end the web 191 and a head 193 on the valve stem 186 for maintaining the diaphragm 185 away from the inner end of the chamber 182 and the annular passage 183.

The operation of my device is as follows: The finger-piece 41 is grasped and moved to the right in Figure 3; thereby reciprocating the rod 40 and opening the bellows 43. At this time the link 51 is reciprocated moving the switch to the "on" position and closing the circuit to the motor (not shown) which operates the windmotor 62. At this time the casing 105 controls the usual operating valves for opening the suction of the stack so that the motor 62 is operated and the player roll 30 is placed in motion. This operation which has just been described

is the normal method of initiating the operation of the roll of a player of an organ or piano. The movement of the member 41 also closes the circuit to the amplifier tubes of the amplifying unit so that said tubes will be heated.

When the roll, however, reaches approximately the first perforation which is in the roll 30 for reproducing a musical composition, the perforation 70 in the roll registers with the passage 73 in the tracker bar 65. This places the pipe or conduit 76 in communication with the atmosphere so that the chamber 81 (Fig. 7) now contains atmospheric pressure which acts upon the diaphragm 153, moving the valve 150 to open position so that the suction from pipe 106 which is connected with the stack 69, will reduce the atmospheric pressure in the pneumatic means or bellows 143, causing the bellows to collapse and through the pin 139 and rod 140 causing reciprocation of the plate or lever 135. When this happens the switch in the box 132 is closed by the arm 133 and the motor 38 (Fig. 13) which operates the turntable of the phonograph is set in operation.

The phonograph in this instance is self-playing and electrically operated and is of a well known type in which the motor 38 through the rotation of the turntable 37 causes the tone arm 34 of the phonograph to be moved to the proper position whereby the needle of the sound box will be placed in registration with the outermost groove of a record 35 so that the record will be brought into playing condition at a period slightly after the starting of the roll 30 in the console. The details for controlling the movement of the tone arm of the phonograph and the application of the needle in the sound box to the record is not described in view of its well known construction and particularly since this construction forms no part of the invention defined in the present application.

The player roll 30 has not been stopped so that as it advances the auxiliary perforation 71 in the said perforation moves into registration with passage 74 in tracker bar 65. This passage 74 is connected by the pipe or conduit 77 with the casing 83, conduit 77 being in communication with the passage 82 in said casing, thereby supplying atmospheric air to the passage 82 which raises the valve 173 so that the passage 93 in the casing is likewise under atmospheric pressure. This passage or conduit 93 extends to the chamber 94 in the casing 92 so that the atmospheric pressure will act on the diaphragm 179, moving the valve 180 in closed position against the inner end of the conduit 176, thereby cutting off communication between this conduit and the conduit 91 which is in communication with the stack 69 in which an exhaust is being created by the usual exhaust pump of the player. Since the vacuum has been cut off to the pipe 176, in the casing 92, the motor 62 is stopped, thereby causing the player roll 30 to be stopped. At this time a musical composition is being reproduced by the phonograph and the roll in the organ console is in a waiting position to be started again when the phonograph has completed its reproduction.

As soon as the needle of the sound box of the phonograph has reached the innermost concentric groove, the switch arm 125 (Fig. 12) comes in contact with the switch member 126, thereby closing the circuit to the solenoid 120. When this occurs the valve 121 (Figs. 4 and 5) is raised, thereby opening the inner end of the

pipe 116 to the chamber 117 which is in communication with the atmosphere through the bleeder passage 118. Since the pipe 116 is connected with the pipe 100 (Fig. 2) and the last-
5 mentioned pipe is in communication with the chamber 101 in casing 83, atmospheric pressure will be supplied to said chamber and act upon the diaphragm 175, thereby opening valve 170 and permitting atmospheric pressure to enter
10 chamber 103 and pipe 102 (Fig. 9). The pipe 102 is connected with the pipe 104 which is in communication with the housing 85 and likewise the stack 69.

When the valve 170 (Fig. 9) has been opened
15 to the atmosphere, atmospheric pressure is supplied to the chamber 172 in the casing 83, thereby acting on the diaphragm 174 and thus closing the valve 173 and likewise the conduit 93 to the atmosphere, or, in other words, cutting off the
20 passage 82 and the conduit 77 from the conduit 93. When the circuit 93 is closed to the atmosphere, the suction from the motor and likewise the stack 69 is again applied to the conduit so that the diaphragm 179 will be acted upon, thereby opening the valve 180 and placing the
25 conduit 91 in communication with the conduit 176 so that the motor 62 will again be placed in operation and the next organ composition begins to play.

30 When the last perforation 72 in the roll registers with opening 75 in the tracker bar 65 the turntable of the phonograph is stopped. This is due to the fact that suction is effected through the pipe 78 leading to the chamber 79 of the
35 casing 80. Suction acts on diaphragm 157 closing valve 155, thereby cutting off atmospheric air to pipe 106 so that suction from the pipe 106 and pipe or conduit 158^a will act on bellows 143^a and move the same to the position shown in Fig. 6. Suction in bellows 143 being relieved
40 the rod 140 will be moved to the left and close the switch in casing 132 and cut off the circuit to the phonograph motor.

When it is desired to have the roll pass over
45 the tracker bar without permitting the roll to produce music the stop or silencer 99 is turned (Fig. 3), thereby opening a valve in the casing 98 for placing the conduit 97 in communication with the atmosphere. Atmospheric pressure acts upon the diaphragm 185 in the chamber 181, opening the valve 187 against the tension of the spring 192, so that atmospheric pressure is supplied to the conduits 182, 87, and 189, the conduit 189 being connected with the stack 69.
50 The suction pump is then drawing atmospheric air into the stack 69 so that the pipes 68 have been relieved of their suction and the automatic operation of the console has been cut out. When it is desired, however, to revert to the
55 automatic operation of the console, the stop 99 is reversely operated, thereby placing the console in proper condition for automatic operation.

It will be appreciated that the necessary re-
60 wind and replay mechanism is included in this console for the player roll 30, but since it forms no part of the present invention description of this matter has been avoided.

While I have shown an organ and a console
65 connected with the organ for operating the same, it will be appreciated that a phonograph may be embodied in a self-playing piano and wherever the term "console" is employed it is intended to include the automatic mechanism
70 for operating the player piano.

While I have shown a construction in which the operation of the phonograph is initiated by the actuation of the rod 140, it will be appreciated that a coin-controlled mechanism may be employed for causing closing of the switch that operates the motor for revolving the turntable of the phonograph. By this construction it will only be necessary to employ the co-operating perforations 70, 73 and 71, 74. The perforations 72 and 75 will not be required in the coin-controlled mechanism since the last-mentioned perforations co-operate to stop the motor which revolves the turntable. In the coin-controlled mechanism the stopping of the turntable will be automatic when the record has been completed.

The magnet 120, shown in Figs. 4 and 5, is energized at a self-stopping point in the playing operation of the coin-controlled mechanism, thus taking the place of the contacts 125 and
85 90 95

I claim:

1. In combination, a self-playing musical instrument and a phonograph, means for operating the musical instrument alternately with the phonograph the musical instrument including a tracker bar having passages and comprising a player roll provided with a plurality of perforations adapted to be aligned with passages in the tracker bar of the musical instrument, a bellows in communication with a passage in the tracker bar and having valve-controlled connections with the exhaust pump of the musical instrument, a piston valve acted on by atmospheric pressure when a perforation has aligned with the passage in the tracker bar for connecting the bellows with the exhaust pump of the musical instrument and causing movement of the bellows, a circuit, a motor for operating the phonograph and included in the circuit, an electric switch actuated by the bellows for closing or opening the circuit to the motor of the phonograph, and means for stopping the player roll when the phonograph is placed in operation.

2. In combination, a self-playing musical instrument and a self-playing phonograph, means for operating the musical instrument alternately with the phonograph the musical instrument including a tracker bar having passages and comprising a player roll provided with a plurality of perforations adapted to be aligned with passages in the tracker bar of the musical instrument, an electric circuit, a motor in the circuit for operating the phonograph, a switch in the circuit, means for closing the switch said means being placed in operation when a perforation in the roll aligns with a passage in the tracker bar, and means for causing stoppage of the player roll just before the phonograph is placed in operation.

3. In combination, a self-playing musical instrument and a self-playing phonograph, means for operating the musical instrument alternately with the phonograph the musical instrument including a tracker bar having passages and comprising a player roll provided with a plurality of perforations adapted to be aligned with passages in the tracker bar of the musical instrument, an electric circuit, a motor in the circuit for operating the turntable of the phonograph, a switch in the circuit, means for closing the switch, said means being placed in operation when a perforation in the roll aligns with a passage in the tracker bar, means for causing

- stoppage of the musical instrument at approximately a time when the phonograph is placed in operation, means for cutting off the phonograph when the record has been completed, and means for initiating operation of the player roll when the phonograph has been stopped. 80
4. In combination, a self-playing musical instrument and a self-playing phonograph, means for causing alternate operation of the musical instrument and the phonograph and comprising means for initiating operation of the musical instrument, a tracker bar having a plurality of passages, the musical instrument including an exhaust pump, a player roll having a plurality of perforations at the termination of the series of perforations for reproducing a musical composition and adapted to be alined consecutively with the perforations in the tracker bar, a diaphragm acted on one face by the exhaust pump of the musical instrument, a pneumatically operated means, a valve controlled conduit leading from the exhaust pump to the pneumatic means, a valve controlling said conduit and actuated by the diaphragm to closed position by the exhaust pump, a pipe connecting an auxiliary passage in the tracker bar with the opposite side of the diaphragm for creating atmospheric pressure on the diaphragm to open the valve and operate the pneumatic means, an electric circuit, a motor for operating the phonograph, a switch in the circuit connected with the pneumatic means and adapted to be closed when the pneumatic means is operated, and means for causing stopping of the console player roll when the phonograph is set in operation. 100
5. In combination, a self-playing musical instrument and a self-playing phonograph, a player roll, means for operating the musical instrument and likewise the player roll, means for operating the phonograph, a tracker bar having passages, the player roll having auxiliary perforations adapted to be alined with passages in the tracker bar of the musical instrument, means pneumatically actuated when an auxiliary perforation in the roll alines with a passage in the tracker bar for causing operation of the phonograph, means pneumatically actuated when a second auxiliary perforation in the roll alines with a passage in the tracker bar for causing the operating means for the musical instrument to be stopped. 115
6. In combination, a self-playing musical instrument, a self-playing phonograph, a player roll, means for operating the musical instrument and likewise the player roll, means for operating the phonograph, a tracker bar having passages, the player roll having auxiliary perforations adapted to be alined with passages in the tracker bar of the musical instrument, means pneumatically actuated when an auxiliary perforation in the roll alines with a passage in the tracker bar for causing operation of the phonograph, means pneumatically actuated when a second auxiliary perforation in the roll alines with a passage in the tracker bar for causing the operating means for the musical instrument to be stopped. 130
- the operating means for the musical instrument to be stopped, means for stopping the phonograph when the reproduction of a record has been completed, and means for starting the player roll. 85
7. In combination, a self-playing musical instrument and a self-playing phonograph, a player roll, means for operating the musical instrument and likewise the player roll, means for operating the phonograph, a tracker bar having passages, the player roll having auxiliary perforations adapted to be alined with passages in the tracker bar, means pneumatically actuated when an auxiliary perforation in the roll alines with a passage in the tracker bar for causing operation of the phonograph, means pneumatically actuated when a second auxiliary perforation in the roll alines with a passage in the tracker bar for causing the operating means for the player roll to be stopped, means for stopping the phonograph when the reproduction of a record has been completed, and means pneumatically operated for actuating the player roll. 90
8. In combination, a self-playing musical instrument and a self-playing phonograph, a player roll means for operating the player roll, means for operating the phonograph, a tracker bar having passages, the player roll having auxiliary perforations adapted to be alined with passages in the tracker bar, means pneumatically actuated when an auxiliary perforation in the roll alines with a passage in the tracker bar for causing operation of the phonograph, means pneumatically actuated when a second auxiliary perforation in the roll alines with a passage in the tracker bar for causing the operating means for the player roll to be stopped, means caused to be actuated when the reproduction of a record of the phonograph has been completed for starting the player roll, and means pneumatically operated when a third consecutive perforation in the roll has alined with a corresponding passage in the tracker bar for causing a discontinuance of the operating means for the phonograph. 105
9. In combination, a self-playing musical instrument and a self-playing phonograph, a player roll in the musical instrument means for operating the player roll, means for operating the phonograph, a tracker bar having passages the player roll having auxiliary perforations adapted to be alined with passages in the tracker bar, means pneumatically actuated when an auxiliary perforation in the roll alines with a passage in the tracker bar for causing the operating means for the player roll to be stopped, means electrically operated when the reproduction of the record of the phonograph has been completed for causing starting of the player roll, and means pneumatically operated when a third consecutive perforation in the roll has been alined with a corresponding passage in the tracker bar for causing discontinuance of the operating means for the phonograph. 115
- LOUIS LUBEROFF. 140
